MOP

Filed Nov. 3, 1930

UNITED STATES PATENT OFFICE

CHRISTINE M. ANDERSON, OF CINCINNATI, OHIO

MOP

Application filed November 3, 1930. Serial No. 493,131.

This invention relates to improvements in mops or brushes used for cleaning and polishing purposes.

Primarily, the object of the invention is a provision of a mop of simple and inexpensive construction.

More specifically, the invention contemplates a simple and inexpensive mop head supporting frame from which the head may be readily dismounted if it is desired to clean the fibrous material constituting the head.

Another object of the invention is to provide a novel form of handle and handle attaching means whereby the handle may be interchangeably used with a plurality of mops or brushes.

Stated broadly, the invention contemplates a mop head frame composed of a plurality of mop head supporting elements, each made of flat metallic stock, and to one of which elements a handle is secured by means of a plate attached to the handle and adapted to be secured firmly against the flat surface of said supporting element, the handle plate having depending portions or flanges embracing the side edges of the mop head supporting element to impart rigidity to the connection between the handle and frame.

With these and other objects in view the invention consists in certain novel details of construction and combinations and arrangements of parts all as will be hereinafter more fully described and the novel features thereof particularly pointed out in the appended claims.

In the accompanying drawings:

Figure 1 is a top plan view of a mop embodying the preferred form of the invention;

Fig. 2 is a perspective view of the mop head supporting frame with the handle attached thereto;

Fig. 3 is a view of the frame, the several elements thereof being shown disassembled;

Fig. 4 is a transverse sectional view taken on the line 4—4 of Fig. 1; and

Fig. 5 is a perspective view of the modified form of the invention with the handle shown in dotted lines.

In order to reduce the cost of production of the mop to what is believed to be a minimum figure, the means for securing the handle to the mop has been reduced to as simple a form of construction as possible and the mop supporting frame has been so designed as to permit it to be made entirely of stock material, that is, the frame for supporting the mop head is composed entirely of a plurality of supporting elements, each formed from flat strips of metal, the several elements being secured together in a simple way and carrying a screw adapted to project through a plate secured to the handle of the mop. This plate seats flat against one of the elements of the supporting frame and is clamped thereto by a nut on the screw that projects through the plate, the connection being given proper rigidity by having the plate on the handle formed with depending portions or flanges at its edges adapted to embrace the side edges of the flat mop head supporting element.

In the preferred embodiment of the invention illustrated in Figs. 1 to 4, the frame consists of a flat bar 10 whose ends are split longitudinally of the bar and the two split portions at each end offset in opposite directions, as illustrated at 11 and 12. Permanently secured to this bar 10 and projecting laterally therefrom is what will be termed an arm 13 whose free end is also split and formed with oppositely offset portions 14, 15. Projecting laterally from bar 10 in a direction opposite to arm 13 is a second arm 16, provided with oppositely offset end portions 17, 18. This arm 16 is detachably secured to the remainder of the mop head supporting frame by a screw 90

19 fast on the arm 13 and bar 10, said screw being received in an opening 20 in the arm 16. As shown in Fig. 1, when the entire frame is assembled the oppositely offset end portions of the bar and arms engage a ring-shaped band 21 of suitable fabric to which are attached the strands, or cleaning elements 22, of the mop head. The dimensions of the bar and arms are such that they distend the band 21 and thereby retain it in the bifurcated offset end portions of the frame.

In this form of mop the handle 23 has a plate 24 attached thereto, said plate being formed with an opening 25 through which the screw 19 also projects. When assembled with the frame, the arm 16 lies flat on the arm 13, and the plate 24 lies flat on the arm 16 with screw 19 projecting through arm 16 and said plate, the plate and arm being firmly clamped on the frame by a nut 26. As will be apparent, if it is desired to remove the mop head from the frame say, for the purpose of washing it, nut 26 is removed and the handle and arm 16 detached. Detachment of arm 16 relieves the tension on the band 21, so that the head can then be readily removed from the end of arm 13 and the opposite ends of the bar 10.

To lend rigidity to the connection between the handle and frame, the opposite edge portions of plate 24 are turned down to form flanges 27, the comparative widths of arm 16 and plate 24 being such that these flanges fit snugly against the edges of said arm. Likewise, to lend rigidity to the connection between arm 16 and the remainder of the frame, the end of arm 16 opposite the offset end portions 17, 18 is turned down, as indicated at 28, and the arm 13 is formed with an aperture 29 adapted to receive this projection 28. This interlocking of projection 28 in opening 29 not only strengthens the connection of the arm 16 on the frame but the projection 28 affords a broader surface against which the thumb can be placed when the frame is being placed in the mop head. That is, when the frame is to be placed in the mop head the bar 10 and arm 13 are first placed in the band of the head after which the arm 16 which has previously been detached, is placed with its bifurcated end against the band and the band extended by the application of pressure against the projection 28. This is preferably done by pressing with the thumb against said projection until the opening 20 comes into registry with the screw 19, whereupon the screw will enter said opening and the projection 28 can be snapped down into the opening 29. After the frame has thus been assembled in the mop head the handle can then be attached by screwing the plate 24 to the arm 16 and screw 19, as before described.

In the form of the invention illustrated in Fig. 5, instead of having four head support-

ing elements radiating from the handle, so to speak, there are only two of such head supporting elements. These two elements are formed simply by two flat, substantially rigid strips or arms 30 that extend in opposite directions into pockets 31 of the supporting portion of the mop head. The length or depth of the pockets 31 is less than the length of the strips 30, so that the juxtaposed ends of said strips are exposed. These juxtaposed exposed portions of the strips lap one another and are fastened together by means of a screw 19^a on the lowermost strip projecting through an opening 20^a in the upperstrip. As in the construction shown in Figs. 1 to 5, the handle 23 has a plate 24 provided with an opening 25 through which the screw 19^a also projects, the plate and strips being rigidly secured thereto by a nut 26^a on the screw 19^a. In this modified construction the plate 24 is formed with the down turned flanges 27 which closely embrace the side edges of the strips 30.

As will be appreciated, the attachment of the handle to the mop head supporting frame is substantially the same in both instances. It is very simple in construction, the connection simply consisting in the plate 24 gripped, so to speak, on one of the bars or strips constituting one of the mop head supporting elements. As a consequence, the mop head supporting frame may be made not only of simple construction but of flat stock. Another advantage of this form of connection is that the handle can be used interchangeably with different mops, so that the manufacturer can furnish a set of mop heads and frames, each mop being usable for a different purpose, but he will only have to furnish a single handle, as that handle can be used interchangeably with the several mops.

What I claim is:

1. In a mop, a mop head having a comparatively soft cleaning or polishing portion and a supporting portion by which the cleaning or polishing portion is carried, a handle, and a bracket by which said handle is connected to the supporting portion of the mop head, said bracket comprising a pair of flat arms the outer end portions of which firmly engage said supporting portion and the inner end portions of which lap each other for a substantial distance, a channel-shaped member to which said handle is attached, said channel-shaped member being snugly engaged about the lapped portions of said arms and holding said arms in alinement, and detachable fastening means rigidly securing said channel-shaped member to said lapped arms and preventing movement of said lapped arms relative to each other.

2. In a mop, a mop head having a comparatively soft cleaning or polishing portion and a supporting portion by which the cleaning or polishing portion is carried, a handle, and

a bracket by which said handle is connected to the supporting portion of the mop head, said bracket comprising a pair of flat arms the outer end portions of which firmly engage said supporting portion and the inner end portions of which lap each other for a substantial distance, an apertured plate to which said handle is attached, said plate being flatly disposed upon the overlapping arm and having a depending flange portion which abuts edges of both of said arms and holds said arms in alinement, and a fastening bolt engaged with the lapping portions of said arms and extending through the aperture of said plate rigidly securing said plate to said lapped arms and preventing movement of said lapped arms relative to each other.

3. In a mop, a mop head having a comparatively soft cleaning or polishing portion, a supporting portion by which the cleaning or polishing portion is carried, and a pair of spaced, oppositely disposed pockets formed in said supporting portion, a handle, and a bracket by which said handle is connected to the supporting portion of the mop head, said bracket comprising a pair of flat arms the outer end portions of which are snugly and firmly received in the pockets of said supporting portion and the inner end portions of which lap each other for a substantial distance on the portion of said band extending between said pockets, a channel-shaped member to which said handle is attached, said channel-shaped member being snugly engaged about the lapping portions of said arms and holding said arms in alinement, and detachable fastening means rigidly securing said channel-shaped member to said lapped arms and preventing movement of said lapped arms relative to each other.

4. In a mop, a mop head having a ring-shaped supporting band by which the cleaning or polishing portion of the mop is carried, a handle, and a bracket by which the ring-shaped supporting band is attached to said handle, said bracket comprising a spreader bar extending diametrically across said band and having means at its ends engaging diametrically opposed portions of said band and holding said band distended in the line of said spreader bar, a pair of flat arms having lapping inner end portions which cross said spreader bar at substantially right angles thereto at a point near its center and having outer end portions which firmly engage and distend said band at points intermediate the points at which it is engaged by said spreader bar, a channel-shaped member to which said handle is attached, said channel-shaped member being snugly engaged upon the lapping portions of said arms and holding said arms in alinement, and detachable fastening means rigidly securing said channel-shaped member to said lapped arms and spreader bar and preventing movement of

said arms and spreader bar relative to each other.

5. In a mop, a mop head having a ring-shaped supporting band by which the cleaning or polishing portion of the mop is carried, a handle, and a bracket by which the ring-shaped supporting band is attached to said handle, said bracket comprising a spreader bar extending diametrically across said band and having means at its ends engaging diametrically opposed portions of said band and holding said band distended in the line of said spreader bar, a flat arm having an inner portion which crosses and is attached to said spreader bar at right angles thereto and having an outer end portion which engages and distends said supporting band at a point intermediate the points at which it is engaged by said spreader bar, a second flat arm having an inner end portion which crosses said spreader bar and overlaps the inner portion of the first arm and having an outer end portion which engages and distends said supporting band at a point opposite its point of engagement by said first arm, a channel-shaped member to which said handle is attached, said channel-shaped member being snugly engaged upon the lapping portions of said arms and holding said arms in alinement, a bolt passing through said spreader bar, arms, and channel-shaped member, and a nut threaded upon said bolt and detachably securing the parts of said bracket in assembly within the ring-shaped supporting band.

6. In a mop, a mop head having a ring-shaped supporting band by which the cleaning or polishing portion of the mop is carried, a handle, and a bracket by which the ring-shaped supporting band is attached to said handle, said bracket comprising a spreader bar extending diametrically across said band and having each of its ends centrally split to provide a pair of tongues one of which is bent upwardly and the other of which is bent downwardly receiving therebetween a portion of said band, a pair of flat arms having inner end portions which lap each other and cross said spreader bar at substantially right angles thereto at a point near its center, and having outer end band-engaging portions similar to those of said spreader bar which firmly engage and distend said band at points intermediate the points at which it is engaged by the ends of said spreader bar, and means by which said arms and spreader bar are held in band-distending assembly and said handle is attached thereto.

7. In a mop, a mop head having a comparatively soft cleaning or polishing portion and a supporting portion by which the cleaning or polishing portion is carried, a handle, and a bracket by which said handle is connected to the supporting portion of the mop head, said bracket including a pair of flat arms the

outer end portions of which firmly engage and distend said supporting portion, and the inner end portions of which lap each other for a substantial distance, means for holding said arms extended in band-distending relation comprising an aperture in the intermediate portion of one arm and an integral lug or projection at the inner end of the other arm which lug is receivable in said aperture, and means at the center of thelapping portions of said arms for holding said lapped arm portions flatly against each other with said lug engaged within said aperture, said last mentioned means also serving to secure said handle to said arms.
